UNITED STATES PATENT OFFICE.

JOHN P. WHIPPLE, OF MILWAUKEE, WISCONSIN.

PAINT-DISTRIBUTER.

SPECIFICATION forming part of Letters Patent No. 292,189, dated January 22, 1884.

Application filed November 20, 1883. (Model.)

To all whom it may concern:

Be it known that I, JOHN P. WHIPPLE, a citizen of the United States, residing at Milwaukee, in the county of Milwaukee and State 5 of Wisconsin, have invented new and useful Improvements in Paint-Distributers, of which the following is a specification.

My invention relates to that class of machines used to distribute pigments in fine-art 10 painting, and has for its object to improve the manner of attaching to the wind-wheel the pitman which operates the needle-operating arm, the manner of connecting the needle-operating arm to the pitman, the manner of supporting 15 the needle-operating arm, the manner of attaching the needle to said arm, the manner of supporting and guiding the bow-needle, the manner of regulating the stroke of the needle, and the construction of both needles, for the 20 attainment of which objects I employ means and construction of parts hereinafter particularly described, and illustrated in the accompanying drawings.

Figure 1 of the drawings is a plan view of a 25 pigment-distributing device with my improvements applied thereto. Fig. 2 is a side elevation thereof. Fig. 3 is a detail side view of a part of the device, with the air-tube in section. Fig. 4 is a detail sectional view of the 30 air-supply tubes in section, showing the construction of the seat for the valve. Fig. 5 is a side view of the improved eye-needle; Fig. 6, a plan view, showing the construction when both the eye and the bow needles are used together. Fig. 7 is a plan view of the cover or 35 cap for the wind-wheel and working parts of the machine. Fig. 8 is a detail view of a part of the device, showing in section two air-tubes. Fig. 9 is a perspective of the improved bow- 40 needle. Fig. 10 is a vertical section through the wind-wheel, showing the bow-needle.

In said drawings, the letter A indicates the hand-piece; B, the pipe for supplying the compressed air to the needles through the branch 45 pipe C; D, the pivoted arm for controlling the entrance of the air from flexible pipe E to the pipe B; and F is another branch pipe for the passage of the air to the wind-wheel. The parts so far described are all of the old construction.

To the side of the hand-piece A there is se-

cured a plate, H, by means of set-screws a, passing through slots b in the plate, so as to permit the plate to be adjusted longitudinally by means of a lever passed downwardly from 55 the top of the hand-piece, and provided with a laterally-projecting stud, c, at its lower end, engaging with or fitting into a notch, d, made in the plate. By attaching the adjusting-lever as described, it can be operated by the 60 thumb of the hand which holds the piece A, so as to quickly, easily, and accurately adjust the needle connected to a part of said plate under the pipe which supplies the air thereto. The plate H has a flange or plate, H', projecting laterally therefrom at right angles thereto, which flange or plate has a post or pin rising from the top, on which the wind-wheel G is 65 slipped, so as to be revolved thereon by the air-jet from the pipe F. The top of the wind-wheel is provided with a headed pin, e, which can be shifted from one to another of several 70 holes made in the wheel therefor, so as to change the throw of the pitman J, which is held to the wheel by passing the said pin 75 through an eye at one end of the pitman. By forming the pitman with the eye and the holding-pin with the head, the pitman cannot be shaken from off the holding-pin.

The needle-operating arm K is formed between its ends with an eye, f, into which one end of the pitman will be hooked or linked, so that the two devices will be securely held together. This arm rests at one end upon a flange, L, extending up from the plate H', the 80 top edge of which flange is inclined downwardly from the end next to the wheel to the end farthest therefrom, at which end it has a stop-projection, g. The object of providing this flange is to afford a rest for one end of the 85 needle-operating arm, so that the needle may not vibrate in its longitudinal movement, and the top edge is inclined so that the inclination of the needle in its movement may be maintained without variance. The opposite end 90 of the needle-arm is bent and fits into the vertical opening in a post, h, rising up from a movable arm, i—in this instance pivoted to a lug, h', projecting from the plate H'—so as to allow the needle-arm to swing, and forming 95 one arm of a link, the other arm, i', of which connects the needle-operating arm with a le-

ver, M. The arm *i* of the link fits over the post or pin *h*, and at the other end is pivoted or riveted to the lever M, which lever is fulcrumed or pivoted to the plate H', as shown 5 in Fig. 1. The plate H' also has a catch, *j*, to engage with the edge of the ordinary cap or cover, N, or a lip thereon, so as to hold said cap down and over the wind-wheel and needle-operating mechanism, to protect the same from 10 injury. The lever M is connected with a spring, O, of any suitable kind, which in this instance is riveted at one end to the lever, and bears at the other end against the plate H, so that when the lever is pressed to drive forward 15 the needle and then released, the spring will retract the needle to its normal position. This spring also permits the needle to be quickly projected forward, so as to expose a greater surface thereof to the air-jet, and as 20 quickly retracted, so as to regulate the quantity of pigment to be deposited.

By connecting the lever to the needle-arm by means of the link, as described, the extent 25 of the projection of the needle under the air-jet tube can be regulated, and at the same time the length of the needle-stroke lengthened or shortened, for when the lever is pressed so as to project or extend the needle farther under the air-jet tube, the position of the post to which the 30 end of the needle-arm is pivoted is changed, so that, as is apparent, the length of the stroke will be altered. Thus it will be seen that the length 35 of the stroke can be altered by the movement of the lever, as well as by shifting the connecting-point of the pitman to the wind-wheel. The lever M is prevented from slipping or moving upwardly by a rod or pin, *k*, projecting across the top of the same from the plate H.

The needle P, which I will designate as the 40 "eye-needle," is formed with the eye *l* at one end by turning or bending the needle at that end through which the needle-arm passes, so that the two parts are held securely together, although the arm may slide through the eye. 45 The needle tapers from the eye, or from a suitable point between it and the point, so that the amount of pigment to be carried under the air-jet tube may be varied by the gradually-increasing thickness of the needle, as well as 50 by the throw of the needle. The needle will be very small in diameter, and if of the same diameter from end to end would be apt to sag to a slight extent, or to be quite easily diverted from a straight line; but by gradually 55 increasing its thickness from its point to its eye it will be stiffened, so as to possess that advantage over the other form, as well as the other advantages hereinbefore assigned to it. The needle passes through a slotted guide- 60 plate, Q, on the plate H', and through a slot or recess in that portion of the plate H which divides the pigment-receptacle R from the plate supporting the operating mechanism, and then to and under the air-jet tube, its 65 point being under said tube when the parts are standing at rest in their normal position.

A guard, S, pivoted or hinged to the side of plate H, so as to drop over the needle, will hold the latter in place and prevent it from rising up from out of the slot in the plate. The needles 70 may also be held in the slots by the lip *m*, projecting from the cap or cover.

The pigment-receptacle is hinged to the hand piece or plate, as usual, and is of the ordinary construction, with the exception of the 75 guide T. This guide-arm may extend from the plate H, as shown in Fig. 1, or from the pigment-receptacle, as shown in Fig. 6, to the air-jet tube, or preferably to a point just beyond the same, and is provided with a flange at that 80 end, in which is formed a slot for the backbone of the bow-needle, so as to afford a support and guide for that form of needle when it is desired to use such form, instead of the eye-needle in the same device. This bow-needle 85 has its shank *n* flattened at right angles to its backbone *o*, so that when the shank is placed in the slot in the plate H, and in the guide-plate Q, the backbone will set at an angle to the shank, as shown in Figs. 6 and 10. 90 The end of the shank of this needle is slotted, as shown in Fig. 9, so that it may be set down over the needle-arm, the lock thus formed holding it to the arm. I prefer to make the shank with the eye-slot, as the needle can then 95 be more readily put in and taken out of place; but it may be made with an eye instead, if desired.

By constructing the bow-needle and supporting it as described, the small wire which 100 carries the pigment is held from contact with any part of the device, so that it is relieved from the frictional contact that would otherwise exist, and hence it will wear much longer.

If desired, the lug *h'* might be made to slide 105 along the plate H', and be held thereto at any desired point by a set-screw, so as to permit of changing the position of the post *h* for the purpose of altering the length of the needle-stroke.

It is apparent that many other changes may be made without departing from the spirit of my invention.

Having thus described my invention, what I claim is—

1. The combination of the wind-wheel, the 115 needle-operating arm provided with the eye, the pitman connected to the eye of the operating-arm at one end, and provided at the other end with an eye, and a pin with an enlarged end for securing the pitman through 120 its eye to the wind-wheel, substantially as set forth.

2. The combination of the wind-wheel, the tapering needle provided with an eye at one 125 end, the operating-arm passed through the eye of the needle, and the pitman for connecting the needle-arm with the wind-wheel, substantially as and for the purpose set forth.

3. The combination of the wind-wheel, the 130 needle-operating arm provided with the eye, and the pitman connected with the wind-wheel

- and joined to the eye of the operating-arm, substantially as described.
4. The combination of the needle, the operating-arm, and inclined rest for the said arm, substantially as described.
5. The combination of the needle-operating arm, and the needle having an eye and connected with the operating-arm thereby, substantially as described.
- 10 6. The combination of the needle-operating arm, the spring-actuated lever, and means for connecting the said lever and arm, substantially as described.
- 15 7. The combination of the needle-operating arm, the spring-actuated lever, and the link-connection between the said arm and lever, substantially as described.
- 20 8. The combination of the needle-operating arm, the spring-actuated lever, means for connecting said lever and arm, and the guide-rod for the lever, substantially as described.
- 25 9. The combination of the hand-piece, the air-jet tube and pipe for supplying air through said tube to the needle, an adjustable plate carrying the needle, and the lever passing down from the upper part of the hand-piece and connected with the plate carrying the needle, so as to adjust the same, substantially as described.
- 30 10. The combination of the pigment-receptacle, the tapering needle, the pipe for supplying an air-jet to the needle, and means for projecting and guiding the needle in a straight line, substantially as and for the purpose set forth.
11. The combination of the pigment-receptacle, the bow-needle, a support for holding the pigment-carrying portion of said needle from contact with the pigment-receptacle, a pipe supplying an air-jet to the needle, and means for projecting the needle, substantially as described.
12. The combination of the wind-wheel, the needle-operating arm, the pitman connecting the said arm and wind-wheel, the needle having an eye-connection with said operating-arm, an inclined rest for said arm, and the lever for varying the stroke and throw of the needle, substantially as described.
13. The combination of the wind-wheel, the needle-operating arm, the pitman-connection between said arm and wheel, the needle connected to said arm, and the support for the needle extending beyond the pipe for supplying an air-jet to the needle, substantially as described.
14. In a paint-distributer, the bow-needle having its shank flattened at an angle to the bow, substantially as described.
- In testimony whereof I have hereunto set my hand in the presence of two subscribing witnesses.

JOHN P. WHIPPLE.
